UNITED STATES PATENT OFFICE.

BERNARD SCHECHTER, OF ST. LOUIS, MISSOURI.

SEAT.

1,302,226.

Specification of Letters Patent. Patented Apr. 29, 1919.

Application filed October 31, 1918. Serial No. 260,493.

To all whom it may concern:

Be it known that I, BERNARD SCHECHTER, a citizen of the United States, residing at the city of St. Louis, State of Missouri, have invented certain new and useful Improvements in Seats, of which the following is a specification.

This invention relates to seats adapted to be used on trolley and railway cars, omnibus, other vehicles, and the like, and wherever seats are arranged adjacent to an aisle, or the like.

Its object is to provide an adjustable or reversible seat of simple and strong construction, consisting of few parts. By reason of its construction, the seat-back can be shifted to a position adjacent to either of the opposite edges of the seat-bottom or cushion and by that movement the seat support is advanced and tilted to a convenient angle from the horizontal so as to put the seat in a position comfortable for the occupant of the seat. Although this construction is cheap and light, it is adequately firm and rigid.

The seat is hinged to adjacent parts so that it can be readily lifted on either of its opposite side edges and folded up toward the seat-back and may also be dropped readily from folded to usable position.

In the accompanying drawings forming part of this specification, in which like numbers of reference denote like parts wherever they occur,

Figure 1 is a perspective view;

Fig. 2 is a side elevation, the principal parts being shown in dotted lines;

Fig. 3 is a sectional view taken on the line 3—3 in Fig. 2;

Fig. 4 is a detail view on an enlarged scale;

Fig. 5 is a detail perspective view of one of the wall-plates;

Fig. 6 is a detail perspective view of one of the tie-plates; and

Fig. 7 is a detail perspective view of one of the seat-rockers.

The side wall 1 of the vehicle supports the angle iron 2, to which is bolted the wall-plate bracket 3, to which is bolted the housing or wall-plate 4, which forms a support for one end of the seat, the other end being, through intermediate parts, supported by aisle-plate 5. Aisle-plate 5 is supported by pedestal 6.

The seat-back 7 can be moved from one side to the other of the seat 8, being pivoted at 9 to lever 10 and at 11 to lever 12. The opposite end of lever 10 is pivoted to an end of seat-rod 13 and the opposite end of lever 12 is fixed to an end of seat-rod 14.

Seat-rocker lever 15 is fixed to seat-rod 14 and is provided with a stud 16 that projects into socket 17 that is cast integral with seat-rocker 18.

Studs 19 project from opposite ends of seat-rocker 18. Socket 17 is cast integral with seat-rocker 18 and has a vertically depending part 20, in which stud 16 can move. A plate 21 underlies seat-rocker 18 and acts as a seat-rocker guide, groove 22 being formed between the said plate and the seat-rocker guide. A tongue 23 having at its end a hook 24 and cast integral with plate 21 projects through the said groove 22. Hook 24 thus holds seat-rocker 18 in place.

Seat-rocker lever 15 is fixed by collar 26 to shaft 14 and therefore rotates therewith.

Most of the above-mentioned parts are in duplicate, one each being located at each end of the seat-rods 13 and 14.

Plate 21 is fastened above flange 27 on the wall-plate and another plate 21 is fastened above flange 28 on the aisle-plate. Plate 21 is in the form of a flange from a member riveted to wall-plate 4 or aisle-plate 5.

Tie-plate 25 is bolted to plate 21 and also to wall-plate 4 or the aisle-plate 5, and is provided with apertures 35, through which the seat-rods 13 and 14 pass to their connection with the seat-levers 10 and 12.

Double hinges 29 are suitably attached on the top of one pair of studs 19. A hinge-joint 30 allows the seat to be upturned in the direction shown in Fig. 1, while the hinge-joint 31 allows it to be upturned in the opposite direction when on the other side of the seat support.

Studs 32 on the top of the strap of hinges 29 are adapted to center in sockets 33, which assists in keeping the seat from side-swaying or disarrangement of the parts.

It should be understood that the precise curvature of the flanges 27 and 28 and of the plates or guides 21 fastened thereto and within the wall-plate 4 and aisle-plate 5 and the corresponding curvature of the seat-rocker 18, is important in producing exactly the most convenient and easy movement of the parts when it is desired to shift the seat-

back 7 from one side of the seat to the other and the right tilt or angle of the seat for comfort.

This shifting is accomplished by taking 5 hold of the seat-back by the handle 34 and applying force thereto. Seat-back lever 10 being pivoted at 13, as well as at 9, adjusts itself freely to this movement, but lever 12 being fixed to seat-rod 14, causes the same 10 to rotate and thus to cause stud 16 on seat-rocker lever 15 to descend in socket 17 and there to apply force to push seat-rocker 18 in the direction opposite to the direction of travel of seat-back 7 which, on account of 15 the curvature of the flanges 27 and 28, as well as the predetermined degree of travel of seat-rocker 18, results in the seat 8 having an agreeable and comfortable inclination or slant for sitting in the opposite direction 20 when the back 7 has been moved its limit of travel.

Tie-plate 25 is bolted to plate 21 and also to wall-plate 4 or aisle-plate 5 and is provided with apertures 35, through which seat- 25 rods 13 and 14 pass to their connections with levers 10 and 12.

Having thus described this invention, I hereby reserve the benefit of all changes in form, arrangement, order, or use of parts, 30 as it is evident that many minor changes may be made therein without departing from the spirit of this invention or the scope of the following claims.

I claim—

35 1. The combination of a pair of end plates and parts contained in each, the said parts consisting in a movable seat-rocker, a seat-rocker guide fixed to the adjacent plate, a projection from the seat-rocker containing 40 a socket, a stud projecting into the said socket, a seat-rocker lever upon which the said stud is mounted, a seat-rod, with which the said seat-rocker lever is in fixed connection, a seat-back lever fixed to the said rod, 45 a seat-back, pivotal connection between the seat-back and the said lever, another lever pivoted to the seat-back, another seat-rod, the same being in pivotal connection with the other end of the said last-mentioned 50 lever, and a tie-plate having fixed thereto a hooked tongue for binding the seat-rocker in place.

2. The combination of a pair of end plates and parts contained in each, the said parts consisting in a movable seat-rocker, a seat-rocker guide fixed to the adjacent plate, a projection from the seat-rocker containing a socket, a stud projecting into the said socket, a seat-rocker lever upon which the said stud is mounted, a seat-rod with which the said seat-rocker lever is in fixed connection, a seat-back lever fixed to the said rod, a seat-back, pivotal connection between the seat-back and the said lever, another lever pivoted to the seat-back, another seat-

rod, the same being in pivotal connection with the other end of the said last-mentioned lever, and a tie-plate in conjunction with each end-plate and having apertures therethrough for the passage of the seat-rods and having a member projecting therefrom adapted to bind each seat-rocker in place.

3. A structure of the character described comprising a pair of end-plates suitably supported, a movable seat-rocker in connection with each, a seat-rocker guide fixed to each, and having a flange forming a groove underneath each seat-rocker, a tie-plate fixed to each end-plate and having a member projecting from such tie-plate and adapted to limit side motion of the seat-rocker without inhibiting its longitudinal movement, a pair of seat-rods bound into relative position by the said tie-plates located respectively at opposite ends thereof, a pair of levers at each end of the tie-plates connecting the same to the seat-back, one of the said levers at each end being pivoted at each of its ends respectively to the seat-back and to one of the said seat-rods, and the other of the said levers at each end being fixed to the other of the said seat-rods, but pivoted at its other end to the seat-back, a seat-rocker lever fixed to that one of the said seat-rods in fixed connection with one of the said levers at each of its ends, and a socket connection between the said seat-rocker and one end of the said seat-rocker lever, whereby motion can be imparted to the said seat-rocker in either direction by movement of the seat-back in the opposite direction.

4. The combination of a seat, a seat-back, a pair of seat-back levers on each end of the seat-back and pivoted thereto, the inner ends of one of each pair of said seat-back levers being pivotally mounted on one of the seat-rods, the other levers of each pair of said seat-back levers being fast to the other of the pair of seat-rods, a seat-rocker at each end of the seat, each seat-rocker having an elongated socket, and seat-rocker levers fixed to the seat-rod to which the seat-back levers are attached, the seat-rocker levers having lugs which engage in the elongated sockets, whereby when the seat-back is moved in one direction the seat-rockers will be moved in the opposite direction, to change the inclination of said seat.

5. In a device of the character described, the combination of a pair of fixed side-plates, each having inwardly-projecting lugs formed with elongated open slots, a pair of seat-rockers provided with lateral flanges and a central rib to engage in the open elongated slots in the side-plates, each seat-rocker having an inwardly-vertically-slotted lug, a pair of seat-rods, levers extend-

ing from one of said rods and provided with lugs which engage in the vertically-slotted lugs on the rockers, a seat-back, a pair of seat-levers which are fixed at their lower ends to the opposite ends of the seat-rod having the levers fixed thereto, pivots connecting the outer ends of the pair of seat-levers to the seat-back, a second pair of seat-levers pivoted at their lower ends to the

outer ends of the other seat-rod, and pivots connecting said second pair of seat-levers to the seat-back, whereby when the seat-back is moved in one direction the seat-rockers will move in the opposite direction.

In testimony whereof I hereunto affix my 15
signature.

BERNARD SCHECHTER.
